Moen Engage Spot Resist Brushed Nickel Magnetix Six-Function 5.5-Inch Handheld Showerhead, Aug. 20, 2015 <https://www.amazon.com/Moen-26112SRN-Magnetix-Six-Function-Showerhead/dp/B0145VC5YS?th=1> (Year: 2015).*

Primary Examiner — Keith J Wilson

(57) **CLAIM**

The ornamental design for a magnetic handheld shower, as shown and described.

DESCRIPTION

FIG. 1 is a rear, left perspective view of a magnetic handheld shower showing our new design;

FIG. 2 is a front, right perspective view thereof;

FIG. 3 is a front view thereof;

FIG. 4 is a left view thereof;

FIG. 5 is a right view thereof;

FIG. 6 is a rear view thereof;

FIG. 7 is a top view thereof; and,

FIG. 8 is a bottom view thereof.

The broken lines shown on the drawings depict portions of the magnetic handheld shower that form no part of the claimed design.

1 Claim, 8 Drawing Sheets
